UNITED STATES PATENT OFFICE.

GEORGE A. JACOBS, OF CHICAGO, ILLINOIS, ASSIGNOR OF ONE-HALF TO CLAES J. JOHNSON, OF CHICAGO, ILLINOIS.

WINDOW-SASH HOLDER.

Application filed November 9, 1922. Serial No. 599,771.

To all whom it may concern:

Be it known that I, GEORGE A. JACOBS, a citizen of the United States, residing at Chicago, in the county of Cook and State of Illinois, have invented a certain new and useful Window-Sash Holder, of which the following is a specification.

The invention relates to a means for yieldably holding window sashes and the like against movement in the frames provided therefor.

The object of the invention generally stated is to provide a means of this general character which is capable of holding the sash at all times in snug fitting engagement with the frame, taking up any looseness which may exist between the sash and the frame to prevent it from rattling and pounding, to hold it at any desired elevation, to insure a weather-tight contact between the sash and the frame, and to prevent it from binding and sticking in the frame.

A more specific object of the invention is to provide a holding device of extremely simple and inexpensive construction as well as effectual in accomplishing the objects above set forth.

In the accompanying drawings I have shown two embodiments of the invention. Fig. 1 is a face view of a frame such as is employed in automobiles having a sash slideable therein and equipped with a holding device constructed in accordance with my invention. Fig. 2 is a vertical sectional view on an enlarged scale through a portion of the frame and showing one edge of the sash in elevation with my improved holding means applied thereto. Fig. 3 is a similar view showing another form of holding means. Fig. 4 is a fragmentary transverse sectional view showing the sash in position within the groove of a frame member.

Referring first to Fig. 1, 7 designates generally a window frame for an automobile or other vehicle, in which is vertically slideable a window sash 8. The frame 7 may be of any suitable construction. It is shown as comprising opposite side frame members 9 having formed in their inner edges grooves 10 constituting slideways for the opposite side edges of the sash 8.

The sash 8 may also be of any suitable construction embodying side frame members or stiles 11 slideable in the groove 10 as aforesaid. The lower portion of the frame 7 may

be constructed with opposed side walls 12 to form a pocket for receiving the sash when lowered. This pocket is normally closed by a hinged plate 13 in a well known manner. The sash has a suitable handle 14, 60 and the inner side wall of the pocket 12 is shown as provided with a notch 15 in its upper portion to receive the handle 14 when the sash is enclosed within the pocket.

Referring now to Figs. 2 and 3, the holding means which I have provided comprises a bowed member 16 or 16' which may be formed of spring steel or other suitable material, and preferably is formed of round wire stock. The opposite ends of the member are anchored in the edge of the sash and for this purpose are provided with anchoring studs preferably in the form of integral inturned end portions or stems 17 or 17', suitable apertures being provided in the edges of the frame members 11 to receive such stems. The members may be of any suitable shape adapted to enter within the grooves 10 with the bowed portions thereof normally extending beyond one face of the sash (Fig. 2 and dotted lines Fig. 3) so as to engage with one side wall of the groove 10 forcing the opposite face of the sash against the opposite side wall.

In the construction shown in Fig. 2 I employ two holding members at each edge of the sash near the upper and lower ends thereof; and each of said members comprises an intermediate or bowed portion 18 having at one end a shank 19 which carries an in-turned stem 17, and at its opposite end a reversely bent arm 20 also carrying an inturned anchoring stem 17. The upper and lower members are preferably reversely arranged, but the arrangement is such that the bowed portion 18 of each member normally projects beyond one face of the sash and preferably the inner face, as shown in the upper portion of Fig. 2. Thus when the sash is slid into the grooves, the members are forced inwardly against the spring action effected between the bowed portion 18 and the arm 20. The result is, as will be apparent from Figs. 2 and 4, the outer face of the sash is held snugly against the outer wall of the groove 10.

The form of holding means shown in Fig. 3 comprises a single member embodying two bowed portions 18' near the opposite ends thereof connected by an approxi-

mately straight intermediate portion 19' and having at their opposite ends inturned stems 17' which are anchored in the side frame members 11 of the sash. In this instance it will be seen the holding means comprises a pair of bowed portions connected together so as normally to cause the bowed portions to project beyond the face of the frame. In the construction shown in Fig. 2, on the other hand, instead of connecting the members together, the resiliency is obtained by the provision of the arms 20 between the bowed portions and the anchoring stem 17. It will thus be seen that the principle of operation is substantially the same in both cases, and doubtless still other forms might readily be devised within the scope of my invention without departing from the spirit and scope of my invention as expressed in the appended claims.

It will be observed that the holding means serves effectually to take up any looseness or play existing between the edges of the sash and the frame, thus preventing the sash from binding and sticking in the slideways while holding it at any desired elevation. It also serves to hold one face of the sash snugly against one side wall of the grooves provided therefor, thus insuring a close weather-tight contact between the sash and the frame to prevent leakage of air around the sash, and eliminating effectually any rattling, pounding or other objectional noises. The device may be constructed very cheaply and applied quickly and easily and without the exercise of any especial skill.

Obviously the application of the invention is not limited to the automobile industry, for it will be apparent that it may be used to advantage in a great many instances whether it be upon windows, screens, doors or similar closures.

I claim as my invention:

1. A holding device for window sashes and the like adapted to be secured upon the

outer edge of the sash stile and bent from a piece of wire stock to form between its ends a bowed portion and a connecting portion constructed to permit the bowed portion to yield under pressure exerted from one side of the sash while the ends of the device are pivotally but non-slidably secured to the outer edge of the stile.

2. The combination with a frame having grooves and a sash slidable in said grooves, of holding means for the sash including a device bent from a single piece of spring wire to form an intermediate portion, and fastening devices at opposite ends of the device extending in a direction perpendicular to the intermediate portion and adapted to be embedded in the edge of the sash adjacent the bottom of the groove in which it operates and to hold the intermediate portion yieldably against one side wall of the groove.

3. A holding means for window sashes and the like comprising a spring member having at its extreme ends perpendicularly disposed anchoring stems and a bowed portion between the ends of the member normally projecting beyond one face of the sash when such ends are anchored in the edge of the sash.

4. The combination with a frame member having a groove therein and a sash, one edge of which is slidable in said groove, of a device carried by said edge of the sash within the groove and adapted to exert pressure on one side wall thereof whereby to hold the sash frictionally against the opposite side wall of the groove, said device comprising a bowed spring member the opposite ends of which are adapted to be embedded in the sash with the bowed portion normally extending beyond the plane of one side wall of the sash.

In testimony whereof, I have hereunto affixed my signature.

GEORGE A. JACOBS.
